[57] CLAIM

The ornamental design for a razor or similar article, as
shown and described.

DESCRIPTION

FIG. 1 is a left side elevational view of a razor or similar
article showing my new design. The right side eleva-
tional view is a mirror image thereof.

FIG. 2 is a front elevational view thereof.

FIG. 3 is a top plan view thereof.

FIG. 4 is a bottom plan view thereof.

FIG. 5 is a rear elevational view thereof.

FIG 1

FIG 2

FIG 5

FIG 3
